UNITED STATES PATENT OFFICE.

HARRY E. COURSON, OF DEWAR, OKLAHOMA.

SPARK-PLUG.

1,361,688.

Specification of Letters Patent.

Patented Dec. 7, 1920.

Application filed May 19, 1919. Serial No. 298,124.

To all whom it may concern:

Be it known that I, HARRY E. COURSON, a citizen of the United States, residing at Dewar, in the county of Okmulgee and State 5 of Oklahoma, have invented new and useful Improvements in Spark-Plugs, of which the following is a specification.

This invention relates to spark plugs particularly designed for igniting explosive 10 gases or charges in internal combustion engines, and one object of the same is to provide a novel form of divided electrode adapted to produce multiple spark gaps, and also to reduce the tendency of carbon to 15 accumulate and be retained on the electrode to a minimum by agitating and intensifying the electric current traversing parts of the divided electrode and thereby forming vicious sparks that will burn out the carbon 20 adjacent to and in the gaps and whereby the electrode will be maintained in good working order with obvious advantages in the explosion of the gases within a cylinder of a combustion engine. A further object 25 of the invention is to provide a divided electrode of such form and disposition of parts that the electric current will regularly follow the components thereof as the course of least resistance and be prevented from being 30 deflected to an adjacent conducting part of the spark plug and thereby effect a succession or multiplicity of sparks of gradually increasing intensity with material advantages in the general operation of the 35 spark plug and the automatic maintenance thereof in a comparatively cleanly condition.

A further object of the invention is to 40 generally improve the construction of spark plugs and avoid therein the formation of cavities or recesses as far as practicable in the parts thereof exposed to the interior of a combustion cylinder or chamber and also to render devices of this class more efficient 45 and certain in their service as ignition means relatively to confined gas charges.

With these and other objects and advantages in view the invention consists in the preferred construction and arrangement of 50 the several parts which will be more fully hereinafter described and claimed, and capable of modification in the proportions, dimensions and details of construction within the scope of the claims.

55 In the drawing—

Figure 1 is a side elevation of a spark

plug embodying the features of the invention.

Fig. 2 is a transverse vertical section of the plug.

Fig. 3 is a bottom plan view of the plug.

The numeral 5 designates the core of the plug which is preferably formed of porcelain and has a bore 6 extending centrally therethrough and, as usual, is provided with a lower and enlarged end 7 formed with a shoulder as at 8 where it intersects the main body of the core. The lower enlarged end 7 is formed with a central recess or socket 9 into which opens the bore 6, the upper extremity of the core 5 being tapered as at 10. Fitted over the core 5 is a steel hexagonal body or attaching base 11 of tubular form for easy application over the said core, and formed with a lower reduced exteriorly 15 screw-threaded extremity 12 having an inwardly and upwardly beveled edge 13, the upper end of the body or base 11 being formed with an annular recess 14. The lower beveled edge 13 of the body or base 11 is normally adjacent to and aligns with the shoulder 8 provided by the lower enlarged extremity 7 and the core 5, a copper and asbestos gasket 15 being introduced 20 between the said lower end of the body or base and the shoulder 8. On the upper tapered extremity 10 of the core 5 a frusto-conical porcelain sleeve 16 is applied and has its lower end fitted in the annular recess 14 at 25 the upper end of the body or base 11, and when the parts are assembled the upper end of the sleeve 16 practically coincides with the upper end of the core. Inserted through the core 5 is an electrode 17 having a lower 30 flange 18 to fit against the upper annular end wall of the recess 9, and from the center of the said electrode a pin 19 projects and provides a spark terminal. The upper extremity of the electrode 17 is screw-threaded a suitable distance as at 20 and after this electrode has been inserted 35 through the core 5, a washer 21 having a peripheral flange 22 is applied thereover so that the flange surrounds and fully embraces the upper end of the sleeve 16, a spring washer 23 and nuts 24 and 25 being applied to the upper portion of the electrode to 40 tightly assemble the parts and to provide means for attaching an electric wire which 45 is held in place by the usual form of binding screw 26.

One of the most essential features of the improved structure is the provision of a plurality of conductors 27, 28, 29 and 30, practically of T-shape form or each having a shank 5 31 fixed within the enlargement 7 at the lower end of the porcelain core 5, and also all provided with T-heads, the head of the conductor 27 being longer than the remaining heads and having its outer end adjacent 10 to a grounding pin or conductor 32 partially embedded in the enlargement 7 and engaging the lower screw threaded extremity 12 of the body or base 11. The heads of all of the conductors 27, 28, 29 and 30 are bent in 15 arcuate form and disposed in volute arrangement, the conductor 30 having its head bent into an abrupt curved form so that one end thereof will be adjacent to or form a gap in relation to the pin 19 at the lower 20 end of the electrode 17. Between the ends of the heads of the conductors 27 to 30, inclusive, spark gaps 33 are formed and by means of the volute arrangement or disposition of the heads of these conductors they 25 provide a means of least resistance to encourage the current to traverse the same without liability of jumping from the conductors to an adjacent conducting member. In fact, the interposition of the enlargement 30 7 which is of non-conducting material, between these conductors 27 to 30, inclusive, and the nearest conducting metal component of the spark plug will insure a traverse 35 of the current relative to the said conductors and the production of a multiplicity of sparks by means of the successive gaps and thereby the sparks are regularly intensified from the first conductor 27 to the last conductor 30 of the series, on account of the 40 resistance caused to the free course of the current by the added spark gaps and between the conductor 30 and the pin 19 will be the greatest in its strength or explosive efficiency. The ends 34 of the conductors 45 27 to 30 are also bent outwardly at right angles to produce large or broad sparking surfaces at the gaps and thus increase the size of the sparks. By having the plurality of gaps and a certainty in the traverse of 50 the current through the several conductors, the carbon or other deposits on the end of the spark plug or the enlargement 7 adjacent to the gaps between these conductors and in the gaps will be burned out and as 55 a consequence the active end of the spark plug within the combustion cylinder or chamber will be automatically maintained in a comparatively cleanly condition and require less attention and repair than is the 60 case in ordinary forms of spark plugs.

It is to be understood that in applying the improved plug to a cylinder, the screw-threaded extremity 12 is secured, as usual, in the cylinder head and the conductors forming the divided electrode and the pin 19 of

the main electrode 17 will be exposed within the cylinder.

The core 5 of porcelain or other analogous non-conducting material is fully inclosed by the sleeve 16 and attaching base 11 and is 70 consequently shielded or protected against breakage by being struck by a wrench or other tool during removal of adjacently located plugs, it being apparent that the said sleeve might be broken or fractured without 75 injury to the core and the perfect working order of the plug.

The improved plug will be found particularly advantageous in creating more power in the explosion of the gas in the 80 cylinder for the reason of the intensifying of the sparks and the virtual formation of a ball of fire on the pin 19 at the end of the electrode 17.

I claim—

1. In a spark plug, a central electrode having a terminal pin, an insulating element in which the said electrode is mounted and at the lower end of which the said pin is exposed, and a plurality of conductors arranged in volute form in the lower end of the insulating element and trending inwardly from the outer portion of the face of the said element and the conductor closest to the center of the element having a decided 90 inward bend radially with relation to the pin, and providing a divided electrode with a multiplicity of spark gaps, the one conductor having its one end directed inwardly to form a spark gap with the said pin, a 95 grounding device forming a spark gap with the outermost of the said conductors.

2. A spark plug having a central electrode with a pin, having a vertically straight terminal, and a plurality of conductors arranged in volute form around the pin, the innermost conductor having one extremity inwardly deflected toward the pin, the conductors forming a multiplicity of spark 100 gaps, the conductors being insulated from the 105 electrode and its pin.

3. A spark plug comprising a plug with a bore therethrough and having a lower enlarged extremity, an electrode extending through the plug and having a pin at its 110 lower end with an exposed straight terminal at the center of the lower enlarged extremity of the plug, a plurality of conductors mounted in the lower enlarged extremity of the plug and arranged to trend inwardly from 115 a point adjacent to the periphery of the face of the plug in volute form toward the central pin of the electrode, the conductor closest to the pin having an inner bent extremity directed toward the pin, the conductors providing a divided electrode with a multiplicity 120 of spark gaps, a ground connecting device being provided to form a spark gap with the outermost of the said conductors.

4. A spark plug comprising an insulating 130

- plug member having a bore therethrough and a lower enlarged end and upper tapered extremity, a connecting base of metal fitted over the lower portion of the plug and having a lower screw threaded extremity for attaching purposes, a copper and asbestos washer inserted between the lower end of the said base and the enlargement of the plug, an electrode extending through the center of the plug member and having a lower pin with an exposed straight terminal at the lower portion of the enlargement of said member, a plurality of conductors held within the enlargement of the plug member and arranged in volute form to extend from the outer portion of the face of said member inwardly toward the center so that the last conductor will provide a spark gap with the said pin, the conductors providing a plurality of spark gaps, a ground connection coöperating with the outermost of the conductors, an insulating sleeve fitted over the upper tapered extremity of the plug member and extending into the upper end of the connecting base, and means for securing the sleeve and base in position and connecting all of the parts of the plug in operative relation.
5. A spark plug having a central electrode pin and a plurality of conductors insulated from and arranged in volute form around the pin and provided with outwardly projecting angular ends exposed to form a multiplicity of extended spark gap surfaces. 30
6. A spark plug having a central electrode with an exposed insulated pin having a straight terminal, and a plurality of conductors insulated from and arranged in volute form around the pin from an outer terminal conductor separated a maximum distance from the pin inwardly toward the latter. 35
7. A spark plug having a central electrode with an insulated exposed central pin, and a plurality of conductors insulated from and arranged in volute form around the pin from an outer terminal conductor separated a maximum distance from the pin inwardly toward the latter. 40

In testimony whereof I have hereunto set my hand in presence of two subscribing witnesses.
